UNITED STATES PATENT OFFICE

105,783

DESIGN FOR A PLATE OR THE LIKE

Fritz Teipelke, Bohm Leipa, Czechoslovakia, assignor to Continental Ceramics Corporation, New York, N. Y., a corporation of New York

Application April 8, 1937, Serial No. 68,630

Term of patent 7 years

To all whom it may concern:

Be it known that I, Fritz Teipelke, a citizen of Germany and a resident of Bohm Leipa, Czechoslovakia, have invented a new, original, and ornamental Design for a Plate or the like, of which the following is a specification, reference being had to the accompanying drawing, forming part thereof.

The figure is a plan view of a plate, showing my new design.

The ornamentation shown within the dotted line is identically continued around the border of the plate.

I claim:

The ornamental design for a plate or the like, as shown and described.

FRITZ TEIPELKE.
